ABRASIVE SHEET SUPPORT SYSTEM

Leonard W. Reames, Howell, Mich., assignor to Edward J. Sopak, Howell, Mich., and Thomas L. Draper, Birmingham, Mich.

Filed Feb. 18, 1963, Ser. No. 259,276

3 Claims. (Cl. 51—378)

This invention relates to the abrasive art; and more particularly to a support system for abrasive sheets for use on rotary abrading machines.

The problem

In the grinding or dressing of surfaces such as of metal castings, automobile bodies for repainting and the like, the rotary abrasive machine has been found to be particularly desirable. The rotary action tends to render the abrasive self-cleaning by rejecting the material removed from the surface and thus reduces the clogging of the abrasive grit that would otherwise occur.

Early abrasive sheet support systems merely comprised a sheet of abrasive material cemented to a rubber backing disc. However, because the rubber backing disc acted as a heat insulator, early clogging resulted from the fact that paint and other materials removed from a surface were rendered gummy by the heat and thus caused early clogging thus overriding the advantage of circular action.

One advance in the art provided a ribbed backing member for the abrasive sheet floatably supported between the abrasive sheet and a rubber drive disc, so that the backing sheet could move relative to the abrasive and thus bring different grains into contact with the work surface upon repeated application of the abrasive thereto. This is set forth in our copending application Serial Number 259,109, filed February 18, 1963, which describes a novel backing disc and its use in the typical prior art mounting system.

However, such typical prior art mounting system as will be hereinafter described was characterized either by:

(a) A substantial number of parts requiring considerable dexterity by the workman in replacing the abrasive sheet when it wore out; or

(b) Welding parts together to reduce the total number. However, this required discarding the more costly and essential part, namely, the rubber drive disc, when replacing the backing disc.

Accordingly, an important advance in the art would be provided by a novel support system for rotary abrasive discs characterized by a minimum of parts, yet providing for the replacement of the separate elements without discarding any other element.

Objects

Accordingly, an important object of the present invention is to provide a novel support system for a rotary abrasive disc.

A further object is to provide a novel support system for a rotary abrasive disc characterized by improved ease of assembly and reduced number of working parts.

A still further object is to provide a novel support system for a rotary abrasive disc characterized by handling minimum parts for abrasive sheet replacement, and further providing backing sheet replacement without loss of the rubber guide disc as has been heretofore characteristic of analogous units of the prior art.

Other objects of this invention will appear in the following description and appended claims, reference being had to the accompanying drawings forming a part of this specification wherein like reference characters designate corresponding parts in the several views.

The drawings

FIGURE 1 is a section view of a typical rotary abrasive sheet support system of the prior art;

2

FIGURE 2 is a section view similar to FIGURE 1, but showing a preferred embodiment of the present invention; and

FIGURE 3 is a section view of a second embodiment of the invention.

Before explaining the present invention in detail it is to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

15

The environment

The environmental surrounding of the present invention comprises an electric motor driven and generally hand held grinder or abrasive machine. Such a machine typically includes a driving motor mounted within a die cast aluminum housing or equivalent. A handle or handles are formed on the housing so that an operator can pick up the unit and manipulate it over a surface to be dressed, such as an automobile fender in repairing the same. A drive shaft is journaled in the housing and is suitably geared to the motor.

The shaft of the machine has an extending stub and this is designated by the reference numeral 10 in FIGURE 1 of the drawings. FIGURE 1 illustrates the known structure which has heretofore been employed, but upon which the present invention provides an advance in the art.

A typical prior structure

Referring now to FIGURE 1 in further detail, it will be noted that stub 10 is provided with an axially extending threaded bore 12 to receive a cap screw 14 used to hold the grinding assembly to the end of the stub shaft 10.

The general components of the system

40 It will be noted that a rubber drive washer 16 of substantial body and thickness is provided with a metal insert 18 at the center. The insert 18 comprises a tubular sleeve flanged at the top end as at 20. The insert 18 is joined as by vulcanizing in the center hole of the rubber drive disc 16.

45 It will be noted that the body of the cap screw 14 is inserted through the bore of the insert 18 for assembly to the end of the stub shaft 10, by threading into the bore 12.

50 A spacer 22 of annular configuration and defining an endless annular channel of U-shaped section opening outwardly, is positioned between the cap 24 of screw 14 and the top flange 20 of the metal insert 18.

According to this prior art embodiment, the spacer 22 55 may be a separate part or fastened as by spot welding to the top of the flange 20 of insert 18. The disadvantages inherent in either of these arrangements will be brought hereinafter.

It will be noted that an abrasive sheet 26 of circular 60 form and having an appropriate center hole is held between the cap 24 of screw 14 and the top side of the spacer 22.

The backing disc, one form being disclosed in our co-pending application Serial Number 259,109, filed February 18, 1963, is designated 28 and is of generally circular configuration. The disc 28 has a center hole 30 whereby it is fitted into the spacer 22 for retention against axial movement. It might be stated that the spacer 22 is flanged over on one side or the other after insertion through the center hole 30 of the disc 28 to assemble the parts. It will be noted that the hole 30 is slightly larger than the bight of the spacer 22, so that the disc

28 is free to rotate relative to the spacer in the space between the drive washer 16 and the abrasive sheet 26.

This is more fully explained by noting that the abrasive sheet 26 is secured against rotation beneath the cap 24 of screw 14 and the top of spacer 22 when the cap screw is tightened down. Thus, the backing disc is movable relative to the abrasive sheet 26 and the rubber drive washer 16 by floating on the spacer 22 in the space between the abrasive sheet 26 and drive washer 16. It will be understood from the foregoing that the sheet 26 and washer 16 move together but can rotate relative to disc 28.

From the foregoing it will be understood that when the workman presses the abrasive sheet against a work surface, the drive disc presses against the back of disc 28 on one side and the work presses sheet 26 against the disc on the other side to lock all 3 elements together.

Advantage of this arrangement is that every time a workman lifts the unit away from the work surface, the backing disc 28 can move slightly relative to the abrasive sheet 26 and the drive disc 16, so that on next contact with the work, different abrasive grain will be forced into contact with the work surface and therefore give the grain previously working, a chance to unload. As discussed above, the backing disc forms a subject of our co-pending application and therefore a more detailed description is not set forth herein. It is sufficient to note that the backing disc 28 is provided with radially extending ridges to provide radial lines of contact between the abrasive grit and the work, and these change upon release of pressure as set forth above.

This prior art structure, as will be noted from the foregoing description, could be made according to one of the following optional arrangements:

(A) A drive washer 16, spacer 22 and disc 28, and abrasive sheet 26 can be separately assembled on the cap screw 24. This provided the greatest number of parts, namely, four as follows:

- (1) Drive washer 16;
- (2) Spacer 22 and disc 28;
- (3) Abrasive sheet 26; and
- (4) Cap screw 14.

It will be understood that this arrangement provides the greatest economy of parts and least manufacturing time, but entails the greatest operator time in fiddling with the various four parts in changing an abrasive sheet or when necessary, the backing disc 28.

(B) The washer 16 and spacer 22 can be connected by spot welding the spacer to the top flange 20, thus providing one less part, to wit:

- (1) Washer 16-spacer 22-disc 28 as a single assembly;
- (2) Abrasive sheet 26; and
- (3) Cap screw 24.

It will be noted that this arrangement provides a lesser number of parts, thus giving greatest economy of operator time for changing the abrasive sheet but a distinct disadvantage from a cost standpoint. Thus, because the spacer 22 and drive washer 16 are an integral unit by spot welding replacement of the backing disc 28 necessarily entails loss of the drive washer 16.

The present invention provides a distinct advance in the art over each of the foregoing prior art arrangements, and a full description will now be provided.

The inventive embodiment of FIGURE 2

In accordance with the present invention, provision is made for changing the abrasive sheet with a minimum disassembly of parts, and the replacement of the backing disc without throwing away the rubber drive washer; thus providing in one advanced unit, the advantages of both of the above arrangements of the prior art, but without any of the disadvantages.

Drive washer of FIGURE 2

The present invention embodies a rubber drive washer as described in the prior art; however, because of its dif-

ferent configuration, it will be provided with a different reference number. Thus, in the embodiment of FIGURE 2, the drive disc is designated by the reference numeral 32. The disc 32 has a larger center hole 34 than 16 previously discussed, to accommodate the larger diameter of the insert 34. The insert 34 has a tubular body portion 36, and an annular base flange 38 having a threaded opening 40 centrally thereof.

Extension shaft

In this embodiment of the invention, as distinguished from the prior art of FIGURE 1, note that an extension shaft 42 is utilized that is provided at its top end with a threaded stud portion 44 that is turned into the thread opening 40 of flange 38 of insert 34. The remaining details of this shaft include opposed flats 46 for application of a wrench and a threaded stud portion 48 at the bottom. By the bottom threaded stud 48, the unit can be attached to the stub shaft of an abrasive machine in the manner of FIGURE 1.

To review a bit, it should be pointed out that joinder between insert 34 and the drive washer 32 is made as by vulcanizing.

Note that the interior of the insert 34 is threaded with a known type of locking thread 50.

Disc holder of FIGURE 2

An important aspect of the present invention resides in the attachment of the backing disc, designated 28, because the same as previously described. This is effected by means of a disc holder designated by the reference numeral 52 that is threaded into the thread 50 in locking relation.

Disc holder 52 includes a tubular body member 54, externally threaded with a locking thread 55 to lock into the previously mentioned locking thread 50. The holder 52 is provided with a top annular flange 56. It will be noted that the exterior thread 55 on body member 54 extends only part way up, so that an annular washer 58 when tightened thereon will be stopped in spaced relation to the top flange 56.

The disc holder 52 is assembled to the backing disc 28 by inserting the body 54 through the center hole 30 of the backing disc and then threading on the annular washer 58 in locking relation. Disassembly of this unit is the reverse. Further assembly comprises threading the bottom exposed portion of the thread 55 into the thread 50 until the washer 58 bottoms on the top flange 60 of insert 34 to provide a locked, assembled relation of parts.

Abrasive sheet retainer of FIGURE 2

As shown in the upper portion of FIGURE 2, the abrasive sheet retainer 62 takes the form of what might be described as an internal thread cap screw. Thus, the unit 62 includes a tubular body 64 internally threaded as at 66 whereby it is threaded onto the upper portion of threaded stud 44 of the shaft 42, that was previously threaded through center hole 40 of washer 32.

Final assembly is made by laying the abrasive sheet 26 on top of the backing disc 28 with the center hole aligned, and then inserting and tightening the capped retainer 62.

Regarding the foregoing embodiment, it is noted that the drive washer 32 and backing sheet disc 28 are dished slightly at the center, so that when final assembly is made, the top flange 68 will lie slightly below the working level of the abrasive sheet as in FIGURE 1, so that only the abrasive grit will contact the work and the top of the cap member 62 therefore does not engage the work to prevent scarring.

Changing abrasive FIGURE 1

From the foregoing, it will be noted that changing the abrasive sheet 26 merely involves removal of the retainer 62; lifting off the sheet; and replacing. The drive washer

32 is never removed, nor is its relationship with the backing disc 28 disturbed.

It will be noted however that if replacement of the backing disc 28 becomes necessary, this can be done very easily by merely removing the disc holder 52; the washer 58; and reassembling. Note that this operation is effected quickly and without loss of the more expensive drive washer 32.

Thus, a substantial advance in the art is provided.

The inventive embodiment of FIGURE 3

The embodiment of FIGURE 3 utilizes a cap screw in accordance with the prior art; but, like FIGURE 2, overcomes the disadvantages of the prior art and functions in a manner generally analogous to the embodiment of FIGURE 2.

A complete description of the FIGURE 3 embodiment now follows:

This embodiment of the invention, mounts directly to the end of the stub shaft 10 and utilizes a cap screw 14.

Drive washer of FIGURE 3

The rubber drive washer of this embodiment is designated by the reference numeral 70, because slightly different from those previous. Centrally, the washer 70 is provided with an insert 72 having a tubular body portion 74, internally threaded as at 76, and with an annular base flange 78. The base flange 78 is provided with a central, unthreaded opening 80 to accommodate the body of the cap screw 14. A radially extending annular top flange 82 completes 72. The insert 72 is vulcanized in place in the center of the drive washer 70.

Disc holder of FIGURE 3

A disc holder, designated by the reference numeral 84, is threaded into the thread 76 in locking relation. The disc holder 84 includes an outer tubular body member 86, externally threaded as at 88, with a locking thread to lock to the previously mentioned locking thread 76. This unit is provided with an annular, radial top flange 90. Inside the body 86, there is press fitted and locked against rotary movement, as by splines, a tubular body member 92, having a top flange 94. It will be noted that the flanges 90 and 94 are axially spaced to accommodate the backing disc 28 for rotation in the U-shaped section channel formed therebetween. The unit 84 is threaded into the thread 76 and both exterior body member 86 and interior body member 92 bottom on the base flange 78 to preserve the channel space between 90, 94. Thus the backing disc 28 and the rubber drive washer 70 are an assembled unit for operation, but can be disas-

sembled for replacement of the backing 28 should this become necessary.

Assembly of FIGURE 2

5 To assemble the system for operation to the stub shaft 10, the cap screw 14 is inserted through the hole in the abrasive sheet 26 and then through the disc holder 84 which with attached disc 28, and then through rubber drive washer 70; and then threaded into the bore 12 of the shaft 10. The same principle of operation is provided as in FIGURE 2. Thus, it will be noted that ease of abrasive disc replacement is provided and that the backing member 28 can be replaced when necessary with a minimum expenditure of time and without other parts replacement.

10 15 What I claim is:

1. A support system for securing a circular abrasive sheet to a threaded shaft comprising an annular drive washer of resilient material, an interiorly threaded insert fixed to said washer at the center thereof, disc holding means including a pair of telescopically assembled axially bored elements having concentric axially spaced flanges defining therebetween an outwardly opening channel, one of said elements being exteriorly threaded for threaded assembly into said insert, a backing disc having a central aperture through which one only of said elements projects to entrap said disc between said flanges with said disc overlying said drive washer, and an abrasive sheet retainer having a radially enlarged flange for confining a central portion of said abrasive sheet against said disc holding means and an axial projection extending through said disc holding means for threaded engagement with said threaded shaft.

2. A support means as defined in claim 1 wherein the disc holding means includes a first element provided with a top annular flange and an externally threaded body, and a second element in the form of a washer threaded onto the body of the first element, the first element flange and the washer defining an outwardly opening channel therebetween.

3. A support system as defined in claim 1 wherein the disc holding means includes a first element having a peripheral flange and an elongated axial extension and a second element including a peripheral flange and an exteriorly threaded axial extension interiorly bored to receive the extension of the first element therethrough, in sliding relationship therewith.
